UNITED STATES PATENT OFFICE

159,465

CUP OR SIMILAR ARTICLE

Robert Y. Allen, Encino, Melvin Shaw, Beverly Hills, and Evan K. Shaw, Los Angeles, Calif., assignors to Metlox Manufacturing Company, Manhattan Beach, Calif., a corporation of California

Application May 10, 1949, Serial No. 2,563

Term of patent 14 years

(Cl. D44—9)

To all whom it may concern:

Be it known that we, Robert Y. Allen, residing at Encino, in the county of Los Angeles, State of California, Melvin Shaw, residing at Beverly Hills, in the county of Los Angeles, State of California, and Evan K. Shaw, residing at Los Angeles, in the county of Los Angeles, State of California, have invented a new, original, and ornamental Design for a Cup or Similar Article, of which the following is a specification, reference being had to the accompanying drawing, forming part thereof, in which:

Fig. 1 is a side elevational view of a cup, or similar article showing our new design;

Fig. 2 is a front elevational view from the left of Fig. 1;

Fig. 3 is a rear elevational view from the right of Fig. 1;

Fig. 4 is a top plan view; and

Fig. 5 is a bottom plan view thereof.

The dominant features of the design reside in the parts shown in full lines.

We claim:

The ornamental design for a cup or similar article, as shown and described.

ROBERT Y. ALLEN.
MELVIN SHAW.
EVAN K. SHAW.
